UNITED STATES PATENT OFFICE.

JOHN CALLOCOTT, OF BRADFORD, ONTARIO, CANADA, ASSIGNOR OF ONE-HALF TO ANDREW T. HOWES AND ONE-HALF TO GEORGE BANNERMAN, BOTH OF BRADFORD, ONTARIO, CANADA.

STEAM AND HOT-WATER FURNACE.

1,041,737.

Specification of Letters Patent.

Patented Oct. 22, 1912.

Application filed July 29, 1911. Serial No. 641,219.

To all whom it may concern:

Be it known that I, JOHN CALLOCOTT, a subject of the King of Great Britain, and resident of the town of Bradford, in the 5 Province of Ontario, in the Dominion of Canada, have invented certain new and useful Improvements in Steam and Hot-Water Furnaces, of which the following is a full specification.

- 10 The invention relates to improvements in steam and hot water furnaces as described in the present specification, and illustrated in the accompanying drawings that form part of the same.
- 15 The invention consists essentially in the novel arrangement and construction of parts, whereby a furnace casing has the headers of the water tube connections arranged therein, one near the bottom of the 20 back wall, and the other supported near the upper part of the front wall, and connected by a plurality of vertical and horizontal pipes parallelly arranged in successive steps and having a horizontal baffle plate supported over the area of the fire box, intermediate of the height of said tubes.
- 25

The object of the invention is to provide a boiler, which by reason of a very large heating surface in proportion to its size, 30 shall be an efficient water heater and steam producer, and which also by reason of its construction, greatly assists in the combustion of all smoke and flue gases.

In the drawings the figure is a perspective 35 view of the invention of the furnace, with one side wall removed therefrom.

Like numerals of reference indicate corresponding parts in the drawing.

Referring to the drawings, 1 is the furnace 40 comprising the walls 2 which are constructed of fire brick or other suitable material.

3 is a sheet metal cover forming the top of the furnace.

45 4 are the shaker grates, common to furnaces of this kind, and operated by the lever 5.

6 is the ash pit of the furnace.

7 are cast iron headers, although it must be thoroughly understood, that these headers may be made of any suitable material. The headers are supported in the interior of the furnace, by the brackets 8, one near the bottom of the rear wall just above the ash pit, and the other near the top of the front wall.

9 are the water tubes, comprising the parallelly arranged vertical tubes 10, which are connected at the bottom thereof to the header at the rear of the furnace.

11 are horizontal tubes leading from the vertical tubes 10, four tubes or more leading from each vertical tube. These tubes are parallelly arranged one above the other, and are connected together in successive steps 65 by means of the elbows 12, short lengths of pipe 13, and the T's 14, the uppermost pipe entering the header, situated near the top of the front wall.

15 is a baffle plate extending over the fire 70 box area of the furnace, beneath the second row of lateral pipes, the short lengths of pipe 13 passing through prepared orifices 16 in the baffle plate.

17 are slots in the rear end of the baffle 75 plate, whereby the baffle plate fits around the vertical tubes. This baffle plate does not fit against the rear or side walls, but a small air space is left therebetween, so that the heat from the fire may readily ascend 80 to the top of the furnace. This baffle plate is for the purpose of baffling the smoke and retaining it in suspension over the fire where it is consumed, and also to distribute the heat evenly throughout the furnace.

18 is the smoke stack, the bottom of which projects some distance below the sheet metal top of the furnace, whereby the heat and gas not finding a ready exit to the atmosphere, curls downward carrying any smoke 90 that might pass over the front end of the baffle plate, back around the sides of the baffle plate into the fire, where it is quickly consumed.

19 is an ordinary safety valve connected directly to the top of the forward header through an orifice in the sheet steel top of the furnace.

5 20 is a water column situated at one side of the boiler near the top and front end thereof. The pipe leading to the bottom of the water column is connected to the second row of lateral tubes from the top.

10 21 are the ordinary gage-cocks secured to the water column, and 22 is the steam gage.

23 is a pipe leading from the safety valve 19 to the pipe connected to the top of the water column, and which also leads 15 to the steam gage through the siphon 22^a.

24 is a pipe leading from the water tank or other water supply, through the rear wall, and into the header situated near the bottom thereof.

20 25 is a valve for regulating the flow of the water through the supply pipe 24.

26 is a blow off pipe connected to the bottom of the rear header, and is for the purpose of emptying the boiler, and removing 25 the sediment therefrom when desired. This blow off pipe is provided with a valve 27. The pipes 11 are inclined slightly upward toward the front header, thereby assisting in removing the water and sediment therefrom, when the blow off pipe is open.

28 is a drip pipe leading from the bottom of the header, at the front of the furnace, to the blow off pipe adjacent to the header at the rear end of the furnace. The drip pipe 35 28 acts as an equalizer and also assists materially in cleaning the forward tank of the furnace, and provides a steam drip when the furnace is used as a steam producer, for as it will be readily understood, when the 40 furnace is used as a steam producer, the tubes of the furnace are only partially filled with water, the steam rising in the upper tubes and into the forward tank.

29 are the feed pipes two in number, one 45 from each end of the header situated at the front of the furnace. These feed pipes are for the purpose of conveying the hot water or steam to the radiators, or other apparatus.

50 30 are the return pipes leading from the radiators to either end of the header at the rear end of the furnace, and convey the hot water back to the furnace, after the said hot water has passed through the radiators.

55 It may be mentioned here, that the front of the furnace is covered by sheet metal, which is divided up into three sections, riveted together.

60 31 is the ash pit door which is situated in the lower section of the sheet metal front.

32 is the furnace door which is provided with a circular damper 33, and is situated in the central section of the sheet metal front.

34 are slide or hinged doors situated in the top section of the furnace front, and 65 provide ready access to the top of the baffle plate 15, and the upper tubes of the furnace, so that any dirt collecting thereon may be readily removed.

It may be mentioned here, that the header 70 or tank situated in the forward end of the furnace may be supported on the outside of the furnace wall, instead of inside, in which case, the horizontal tubes leading thereto will pass through prepared orifices in the 75 said front wall.

This furnace has been found very efficient as a hot water heater and steam producer.

The furnace may be made in all sizes, and its efficiency as a heater, and its power qualities may be considerably increased, by increasing the size of the cast headers and tubes in the furnace. It is found to be very economical, as very little coal is required to keep the water heated, and as it consumes 85 its own smoke, the combustion is perfect.

What I claim as my invention is:

1. In a device of the class described, a lower header, an upper header, vertical tubes extending upwardly from said lower header, 90 upper horizontal tubes extending from the upper ends of said vertical tubes to the said upper header, a plurality of horizontal tubes of various lengths extending from said vertical tubes and paralleling said upper horizontal tubes, and vertical coupler tubes connecting the outer end of each of said horizontal tubes with the horizontal tube immediately thereabove.

2. In a device of the class described, the 100 combination of a furnace casing, a lower header, an upper header, vertical tubes extending upwardly from said lower header, a baffle plate horizontally arranged intermediate of the height of said vertical tubes and 105 spaced apart from the side walls of the said furnace casing, upper horizontal tubes extending from the upper ends of said vertical tubes to the said upper header, a plurality of horizontal tubes of various lengths extending from said vertical tubes and paralleling said upper horizontal tubes, and vertical coupler tubes connecting the outer end of each of said horizontal tubes with the horizontal tube immediately thereabove. 110

3. In a device of the class described, the combination of a furnace casing, a lower header, an upper header, vertical tubes extending upwardly from said lower header, 120 upper horizontal tubes extending from the upper ends of said vertical tubes to the said upper header, a plurality of horizontal tubes extending from said vertical tubes, a series of vertical tubes connecting the outer ends of said horizontal tubes with the horizontal 125 tubes immediately thereabove, a baffle plate

horizontally arranged across the said casing intermediate of the height of said vertical tubes and forming upper and lower chambers in said casing and a smoke stack extending through the top of said casing in proximity to said baffle plate.

Signed at city of Toronto in the Province

of Ontario, in the Dominion of Canada, this 14th day of March 1911.

JOHN CALLICOTT.
